UNITED STATES PATENT OFFICE.

CHARLES P. STEVENS, OF SAN PEDRO, CALIFORNIA, ASSIGNOR OF ONE-THIRD TO BESSIE B. HALE, OF LOS ANGELES, CALIFORNIA, AND ONE-THIRD TO HUGH R. STEVENS, OF SAN PEDRO, CALIFORNIA.

SENTINEL TOWER FOR BANKS.

Application filed May 8, 1925. Serial No. 28,987.

To all whom it may concern:

Be it known that I, CHARLES P. STEVENS, a citizen of the United States, residing at San Pedro, in the county of Los Angeles and 5 State of California, have invented new and useful Improvements in Sentinel Towers for Banks, of which the following is a specification.

This invention relates to an armoured 10 tower adapted to be installed in banks and jewelry stores and is in the form of an observation or sentinel tower so constructed that a guard within the tower may be able to observe various parts of a bank by means 15 of a camera obscura construction mounted in the top of the tower, whereby the images, for instance of the different tellers' windows may be concentrated and projected on a single mirror.

20 Another object of the invention is to provide a sentinel tower of cylindrical shape having a hemispherical top and bottom in order that bullets striking the sentinel tower will glance off rather than penetrate through 25 the sides or top.

Another object of the invention is to provide a sentinel tower having a call board within the interior of the sentinel tower, the call board having a plurality of compartments 30 with electric lights therein which may be individually lighted by a foot operating switch located in each of the tellers' cages, there being a glass panel covering the compartments, having a number corresponding 35 to each of the different tellers' cages, so that when the teller is suspicious of a certain person he may close the switch and thereby call attention to the guard within the tower.

A further object of the invention is to 40 provide a sentinel tower of the character referred to, having a plurality of lateral openings through which a rifle or other firing arm may be projected by the guard within the tower, in order that he may shoot in 45 various directions.

Another object of the invention is to provide a sentinel tower having an electric switch therein, which is adapted to close a circuit to electrically operated doors, in 50 order to close all the doors of the bank at one time.

These objects are accomplished by the disclosure herein set forth, by the following description of the accompanying drawings

illustrating the practical embodiment of the 55 invention, the novel features thereof being pointed out in the appended claims, in which—

Figure 1 is a perspective view of the interior of a bank, showing the sentinel tower 60 as it appears in position.

Fig. 2 is a perspective view of the sentinel tower, parts being broken away and shown in sections.

Fig. 3 is a vertical section taken through 65 the sentinel tower.

Fig. 4 is a horizontal section taken on line 4—4 of Fig. 3.

Fig. 5 is a detailed section taken on line 5—5 of Fig. 3. 70

Fig. 6 is a detailed front elevation showing a shutter for closing the firing holes.

Fig. 7 is a section taken on line 7—7 of Fig. 6.

Fig. 8 is a rear elevation of the shutter 75 as it appears from the interior of the sentinel tower.

Referring by numerals to the accompanying drawings, the numeral 10 designates a hollow pedestal upon which the sentinel tower T is mounted. The sentinel tower T has a cylindrical portion 11 terminating in hemispherical upper and lower portions 12 and 13, and is made up of outer and inner walls of armoured plate 14 and 15, which 85 are secured to a frame work 16, made up of structural steel. The frame work 16 consists of upright I-beams 17, the ends of which are bent on radii corresponding to the hemispherical upper and lower portions 12 90 and 13. The I-beams 17 are connected and braced by horizontal I-beams 18.

The I-beams 17 are secured to the I-beams 18 by welding process and the outer and inner walls of armoured plate 14, are in a 95 like manner secured to the frame 16.

In order to make the sentinel tower bullet-proof, the space between the inner and outer walls 14 and 15 is filled with compressed cotton 19. A plurality of firing 100 holes 20 extend through the walls 14 and 15 and the compressed cotton 19. The firing holes 20 are adapted to be normally closed by inner and outer shutters 21 and 22 respectively, the shutters being connected by a shaft 23 extending through a sleeve 24. The shutters 21 and 22 are rigidly secured to the shaft and a handle 25 is mounted on

- 2
- the inner shutter 22 so that when it is desired to open the firing holes it is only necessary to manipulate the handle 25 which will swing both shutters clear of the openings 20. 5 The shutters may be retained in closed position by a pivotally mounted latch 26 which is adapted to engage a recess 27 formed in the outer edge of the inner shutter 22.

Access to the tower is provided by an entrance opening 28 as is clearly shown in Fig. 2, and if it is necessary to place the tower at a high elevation, a plurality of ladder rungs may be secured to the pedestal 10. The pedestal 10 extends inwardly into the tower and is adapted to receive a flange 29 of a standard 30 supporting a revolving lean back spring chair 31.

The sentinel tower is provided with a floor 32 which is mounted on brackets 33, secured to the frame 16 and a flange 34 secured to the pedestal 10.

A trap door 35 is mounted directly above the entrance 28 and is adapted to close an opening 36 in the floor 32. The door 35 is connected to the floor by a pair of hinges 37 and is provided with a pair of lifting handles 38.

A circulation of air through the tower is provided for by means of an air inlet opening 39 formed in the pedestal below the tower and an air conduit 40 forms a passage between the interior of the pedestal 10 and the interior of the tower T, as clearly shown in Fig. 3.

35 The air inlet opening 39 may be covered with a screen 41 and the upper end of the conduit 40 is enclosed by a screen 42 resting on the floor 32.

The circulation of air through the tower 40 is induced by a fan 43 operated by an electric motor 44. The fan 43 is mounted within a cylindrical housing 45 which projects through the upper portion 12 of the tower. The housing 45 projects a short distance beyond the exterior of the outer wall 14 and has a bevelled edge 46 in order to deflect bullets.

In order to prevent any bullets from entering the interior of the tower through the housing 45, a plate 47 is mounted within the housing 45, directly above the fan 43, the plate being of a smaller size than the interior of the housing 45, in order to allow a circulation of air to pass between the periphery of the plate 47 and the housing 45.

A camera obscura construction generally designated at 48 is mounted on the top of the portion 12 of the tower T and consists of a plurality of laterally projecting tubes 60 49, each of the tubes being provided with a lens 50 at their outer end and a mirror 51 at their inner end, the mirror 51 being positioned at an angle of 45°.

65 A plurality of perpendicular tubes 52 extend through an opening 53 and are posi-

tioned directly below the mirrors 51 in the tubes 49. The tubes 49 are adapted to individually focus and project the image of the tellers' windows and a small portion of the area surrounding, on a mirror 54. Hence, 70 by looking on the mirror 54 the guard may be enabled to see all the tellers' windows and at once observe any irregularity taking place in the bank.

A call board generally designated at 55 is 75 mounted on the inner wall 15 and consists of a plurality of compartments 56 and is covered by a glass plate 57.

Each of the compartments 56 are provided with an electric lamp 58, each lamp being 80 adapted to be illuminated by a foot operated switch located in the teller's cage.

A number corresponding to a number of each teller's window is formed on the glass 85 57 corresponding to each compartment 56.

An electric conduit 59 extends through the pedestal 10, floor 32 and is connected to the call board 55. An electric switch 60, is mounted adjacent the call board 55 and is adapted to close a circuit for electrically 90 operated doors for closing all the exits of the bank at one time.

A powerful electric lamp 61, is mounted in a spherical member 62 and is adapted to illuminate the interior of the tower and also direct light on the mirror 54, the circuit to the lamp 61 being independent of the general lighting system of the bank, so that in case the main wires are cut the guard 95 will still be able to see.

A telephone 63 is adapted to be mounted on a stand 64 secured to the inner wall 15. The telephone may be used for calling the police station or ambulance.

From the construction it will be seen that the sentinel tower affords protection against the ever increasing number of holdup artists who specialize in robbing banks, jewelry stores and the like, and the guard within the tower is relieved of the usual nervous strain which they are usually subjected to when peering through a peep hole for any great length of time.

It will also be appreciated that due to the camera obscura construction and the call board, the guard is enabled to have a clear vision of all the tellers' cages and that any one of the tellers may signal and attract the attention of the guard by closing the foot operated switch in his cage if he should become suspicious of a customer or be held up. The guard may then close all the doors of the bank and prevent the holdup artist from escaping by manipulating the switch 60. If it should be necessary to use firearms the guard may do so by opening one of the shutters and fire in any direction through the firing holes.

125 From the above it will be obvious that a bank or other institution employing the 130

sentinel tower will be avoided by holdup artists and that the trade of such institutions will be increased as their customers will have no fear of being killed or injured during a holdup.

Various changes may be made without departing from the spirit of the invention as claimed.

What is claimed is:

- 10 1. A sentinel tower comprising a frame, an outer wall and an inner wall secured to said frame, said outer and inner walls being made of armoured plate and having a central cylindrical portion terminating in hemispherical ends, the space between said inner and outer walls being filled with compressed cotton, a hollow pedestal supporting said sentinel tower, a floor within the interior of said sentinel tower, said hollow pedestal having a portion extending into the interior of said sentinel tower, an air conduit within said sentinel tower registering with an opening in the portion of the hollow pedestal extending into the sentinel tower, there being 25 an air inlet opening in said hollow pedestal below said sentinel tower and an air outlet in the hemispherical top of said sentinel tower, an electric fan for inducing a circulation of air through the sentinel tower, a 30 revolving chair within said tower mounted on the upper end of said hollow pedestal, a plurality of camera obscuras mounted on the top of said sentinel tower adapted to project images upon a mirror within the sentinel 35 tower and a call board for the purposes set forth.

2. A sentinel tower comprising a frame of structural steel, an outer wall formed of armoured plate secured to said frame, an

inner wall of armoured plate secured to said frame, the space between the inner and outer walls being filled with compressed cotton, a plurality of perpendicular tubes extending through an opening formed in the top of said sentinel tower, a plurality of lateral tubes connecting with said perpendicular tubes, each of said lateral tubes having a lens therein at its outer end, and a mirror set at an angle of 45° at its inner end, a mirror mounted within the interior of the tower directly below said plurality of perpendicular tubes and an electric lamp within a housing above said plurality of perpendicular and lateral tubes adapted to illuminate the interior of said tower. 40 45 50 55

3. A sentinel tower comprising a frame of structural steel, an outer wall formed of armoured plate secured to said frame, an inner wall of armoured plate secured to said frame, said inner and outer walls having a plurality of lateral firing holes, an inner and outer shutter adapted to cover said firing holes, said shutters connected by a shaft, and a handle carried by the inner shutter for opening and closing the shutters. 60 65

4. In a sentinel tower, a call board having a plurality of compartments adapted to be individually electrically illuminated by closing a remote switch located in a teller's cage or any other desirable point, and a switch adapted to close an electric circuit controlling electrically operated doors of the bank or building wherein the sentinel tower is installed. 70

In testimony whereof I have signed my name to this specification. 75

CHARLES P. STEVENS.
